FAIRCHILD & CO., OF NEW YORK, N. Y.

DESIGN FOR A MATCH-BOX.

SPECIFICATION forming part of Design No. 21,892, dated October 11, 1892.

Application filed September 7, 1892. Serial No. 445,271. Term of patent 3½ years.

To all whom it may concern:

Be it known that I, LOUIS FRED HURD, a citizen of the United States, residing at Newark, in the county of Essex and State of New Jersey, have invented and produced a new and original Design for Match-Boxes, of which the following is a specification.

My invention has reference to a new design for match-boxes, and is illustrated in the accompanying drawing, which is a face view of the box.

The box is provided along each edge with a border *a*, made up of reversely-curved sec-

tions, this border being carried around the ends. At the point where the cover fits upon the body is also a scroll or border *b* of the same general character.

What I claim is—

The design for a match-box herein described and illustrated.

In witness whereof I hereunto set my hand in the presence of two witnesses.

L. FRED HURD.
